UNITED STATES PATENT OFFICE.

CHARLES E. STELLER, OF MILWAUKEE, WISCONSIN.

TRANSOM-SUPPORT.

SPECIFICATION forming part of Letters Patent No. 340,015, dated April 13, 1886.

Application filed September 3, 1885. Serial No. 176,177. (No model.)

To all whom it may concern:

Be it known that I, CHARLES E. STELLER, of Milwaukee, in the county of Milwaukee and State of Wisconsin, have invented new and useful Improvements in Pivotal Supports for Transoms; and I do hereby declare the following to be a full, clear, and exact description of said invention, reference being had to the accompanying drawings, and to the letters or figures of reference marked thereon, which form a part of this specification.

My invention relates to improvements in the pivotal supports of transoms.

Figure 1 represents a perspective view of that part of one end of the transom to which the pivotal support is attached with one of the parts of the support attached thereto. Fig. 2 represents that part of one end of the transom-frame to which the supporting part of the transom is affixed together with the supporting-pivot attached thereto. Fig. 3 represents a front view of the device shown in Figs. 1 and 2 in position for use.

Like parts are represented by the same reference-letters in the several views.

By my improvement the supporting-pivot A of the transom B is rigidly secured within the transom-frame C, and upon its protruding end a loosely-fitting washer, D, is provided to prevent contact of the transom with the transom-frame. Said washer is not, however, essential to my device. A recess is formed at E in the respective ends of the transom, for the reception of the metallic block F, in which block is formed a nicely-fitting bearing or aperture for the reception of the protruding end of the pivot A. The block is provided with a face-plate, H, formed at right angles thereto and secured to the face of the transom by

screws I I. It is obvious that by thus forming the supporting-pivot A in a separate piece from the face-plate H and block F, I am enabled thereby to make it from ordinary wrought-iron rods, thus insuring much greater strength in proportion to the diameter of the pivot than could be attained were it formed from cast-iron in connection with the face-plate H and block F. It is also obvious that by forming the pivotal bearing G, as shown, within the block F, it is readily rimmed out to nicely fit the supporting-pivot, and in view of the fact that the block F is sunk into a nicely-fitted recess within the edges of the transom, whereby it is relieved from liability of being broken by side or twisting strains I am enabled to make it of ordinary cast-iron without liability of its being broken, as might otherwise be the case were it formed in a single piece in connection with the supporting-pivot.

It will be understood that a duplicate of the supporting devices shown and described is used at the opposite end of the transom-frame.

Having thus described my invention, what I claim as new, and desire to secure by Letters Patent, is—

In transom-supports, the face-plate H, having right angular portion F and pivotal bearing G, made integral therewith, in combination with the pivot or pintle A, substantially as and for the purpose specified.

In testimony whereof I affix my signature in presence of two witnesses.

CHARLES E. STELLER.
